UNITED STATES PATENT OFFICE.

DONALD MACKENZIE, OF EAST ORANGE, NEW JERSEY, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed February 1, 1926. Serial No. 85,171.

This invention relates to telephone exchange systems and more particularly to the transmission of station call numbers from automatically operated apparatus to a telephone operator.

It is the object of this invention to provide an improved method of transmitting signals to a telephone operator.

In multi-office exchange areas consisting of automatically operated and manually operated offices, telephone calls must be transmitted therebetween with the least inconvenience to the subscriber. In the case of a subscriber whose line extends into an automatically operated office an endeavor is made to have the dialing function the same for interconnection to a manual office as it is for interconnection to an automatically operated office or to a subscriber in the originating office. A well known system for such interconnection employs an indicator at each manual operator's position which is operated automatically under the control of registering mechanism in the automatic office to inform the manual connecting operator of the number and character of the desired connection. Each trunk circuit incoming to an operator's position from a distant automatic office is usually provided with an individual signal lamp, the illumination of which advises the operator that a call is awaiting her attention on the associated trunk. The manual connecting operator in answer to the illuminated signal lamp connects the indicating mechanism common to her position with the calling trunk and the designation of the called line is subsequently set up and displayed before the operator who proceeds to complete the connection. An indicator for this purpose occupies considerable space in each position of the manual switchboard which somewhat cramps the available space for other necessary apparatus. This indicator may be removed from the switchboard position by the use of this invention.

A feature of this invention is to provide a call number signaling device for a manual operator's position whereby a station number dialed by a subscriber into an automatically operated office is transmitted over a trunk to the manual position in the form of current pulses which are translated into an audible pronouncement of said number to the manual operator by excitation of photo-

electric cells from light directed through striations of a film.

These and other features of the invention will be more apparent from a consideration of the following description and appended claims taken in connection with the accompanying drawings.

Referring to the drawings (Figs. 1 to 7), as much of a telephone system embodying the invention is disclosed therein as is necessary to an understanding thereof.

Fig. 1 shows diagrammatically a calling automatic subscriber's line, a line finder switch, a sender, and a district switch of an automatically operated office which may be of the type fully illustrated and described in Patent No. 1,505,171 to F. A. Stearn, together with a trunk circuit from the automatic office to a manual operator's position in the called office.

Figs. 2 and 3 show a call indicating control mechanism at the manual operator's position arranged to be associated with any of the trunk circuits at such position and operated in response to code impulses sent over an interoffice trunk from the mechanical office.

Fig. 4 shows four vertical drums for the thousands, hundreds, tens, and units digits. Each drum carries a film with striations to represent the numbers (0 to 9). That portion of the cylindrical surface of the vertical drums which is covered by striations is of a transparent nature whereas the remainder of said surface is opaque. Enclosed in each drum is a photo-electric cell which is associated with an amplifying circuit (diagrammatically shown) which amplifies the output of the cell. The operator's headset is directly connected to said amplifying circuit. A motor is shown coupled to a horizontal shaft with the gearing necessary for the proper rotation of the vertical drums.

Fig. 5 is a detailed view of the electromagnetic locking mechanism in an operated condition which is individual to the thousands digit drum and which when actuated automatically starts up the driving motor and permits the rotation of all drums.

Fig. 6 shows the same electromagnetic locking mechanism as shown in Fig. 5 but in a released position just prior to the armature roller falling into its slot to arrest the further advance of its associated drum.

Fig. 7 is a partial top view of Fig. 4 giving a view of the driving mechanism and showing the different stages of one complete revolution of any drum during which such 5 drum is actively engaged in announcing its associated numerals. The heavy arcs on the circles of Fig. 7 indicate these stages.

A brief description of the system will now be given. Assuming that automatic subscriber "A" removes his receiver from the hook and dials the office code and numerical digits of the wanted line of a distant manual office, the selective operations of the district selector switch will serve to select an outgoing trunk to the called manual office under the control of the sender registers. After the calling automatic subscriber has dialed the office and numerical digits of the wanted manual subscriber's line the district selector 15 is operated and a connection is extended over a trunk such as 100, 101 to an operator's position in the desired manual office. The illumination of a lamp individual to the trunk circuit advises the operator in the 20 terminating office that a call is awaiting her attention. The manual operator, if idle, then presses the individual assignment key to associate the call indicator mechanism at her position with the calling trunk circuit. 25 Code impulses are then transmitted over the trunk in accordance with the settings of the numerical registers of the sender in the mechanical office to select the proper combination of light valves or shutters, causing 30 the rotation of the drums, illumination of the speech films superimposed thereon and a consequent excitation of the photo-electric cells enclosed in said drums. The designation of the wanted line is accordingly spoken 35 directly to the manual operator. The manual operator completes the connection by inserting the terminating plug of the trunk circuit in the proper jack to ring the called line.

Having thus briefly outlined the present system a more detailed description will now be given. Let it be assumed that the number of the wanted line is NOR 4432. The calling automatic subscriber accordingly 50 dials the office code and numeral digits of the wanted line which digits are registered upon the registers of the sender in the originating office. The selective operation of the district selector switch in the manner well 55 known in the art operates to select a trunk 100, 101 which leads to a manual operator's position in the distant called office represented by the office code NOR. The office and numerical designations are recorded on 60 the registers of the sender in the calling mechanical office. A detailed account of the above operations is not necessary to a proper understanding of the invention and has been accordingly omitted. However, reference is 65 made to the patent to A. E. Lundell 1,464,

084, August 7, 1923 for a detailed description of the system such as herein employed in connection with my invention.

After the completion of selections for selecting an idle trunk to the desired office, 70 a circuit is completed from battery through the back contact and inner lower armature of relay 125, conductor 131, right hand winding of marginal relay 113, winding of relay 114, inner normal contact of relay 116, conductor 117, outer right armature and back contact of relay 108, conductor 100, through the apparatus in the mechanical office including a high resistance circuit in the sender, 75 back over conductor 101, inner armature and back contact of relay 108, conductor 138, outer normal contact of relay 116, left hand winding of marginal relay 113 to ground. Relay 113 being marginal does not energize 80 in series with the resistance of the sender circuit. Relay 114, however, energizes in the circuit just traced. Relay 114 closes a circuit from ground through its armature and contact, winding of relay 115 to battery and ground. 85

Assuming that the plug 126 of the trunk circuit has not been removed from the jack by the operator after the termination of a prior call, relay 110 will be energized by means of a circuit to be hereinafter described. Hence when relay 115 operates, it closes a circuit for itself from battery through its winding and contact and inner left armature of said relay, front contact and outer upper armature of relay 110, back 90 contact and inner left armature of relay 112 to ground. Relay 115 at its right hand armature and contact shunts out relay 114, permitting the latter relay to release. Relay 115 also closes a circuit from battery through the assignment lamp 111, outer right hand armature and back contact of relay 105, conductor 139, front contact and outer left hand armature of relay 115 to ground. The illumination of lamp 111 informs the operator 95 that a call is awaiting her attention on the corresponding trunk.

If, however, the plug 126 is not inserted in a line jack at the time the trunk 100, 101 is seized, relay 110 is deenergized and relay 115 finding no locking circuit again releases as soon as relay 114 has been shunted out. The circuit changing sequence switch in the sender circuit has now progressed to a point 100 where the high resistance has been excluded from the circuit. For a detailed description of the above operations, reference is again made to the patent to Lundell, supra. Marginal relay 113, therefore, becomes energized 105 and completes a circuit from battery through the winding of relay 112 to ground at the contact and armature of marginal relay 113. Relay 112 closes a circuit in shunt of relay 114 as follows: battery, back contact and inner lower armature of relay 125, conductor 110

131, right hand winding of marginal relay 113, contact and outer left hand armature of relay 112, inner normal contact of relay 116, and thence over the tip side of the line and 5 returning as hereinabove described to ground at the left hand winding of relay 113. Relays 114 and 115, therefore, remain deenergized. Relay 112 completes a circuit from battery through the assignment lamp 111, 10 outer right hand armature and back contact of relay 105, contact and inner upper armature of relay 110, contact and inner right hand armature of relay 112 to ground. The lamp 111 is illuminated and the operator 15 observing the same knows that a call is awaiting her attention.

At her convenience the operator responds to the call by depressing the home assignment key 103 which is individual to trunk 20 100, 101. The depression of key 103 operates to associate the trunk with the call indicator mechanism of the home operator's position. A circuit is closed from battery through the winding of relay 218, conductor 132, contact 25 and lower outer armature of relay 110, right hand winding of relay 105, contact of operated key 103, conductor 133, armature and contact of relay 223, back contact and right hand armature of relay 221 to ground. 30 Relay 105 energizes and locks up on a circuit from battery through the winding of relay 218, conductor 132, contact and outer lower armature of relay 110, windings of relay 105 in series, contact and left hand armature of said relay to ground. Relays 35 105 and 218 therefore, lock up independently of key 103 which restores as soon as it is released by the operator. Relay 105 closes a circuit from battery through the assignment lamp 111, outer right hand armature, and front contact of relay 105, interrupter 134 to ground. Lamp 111 is caused to flash in the circuit traced. Relay 105 also closes a circuit from battery through the winding 40 of relay 108, contact and inner right hand armature of relay 105, conductor 135, winding of relay 223, back contact and left hand armature of relay 221 to ground. Relay 108 attracts its armatures and extends the incoming trunk conductors 100 and 101 by way of conductors 136 and 137 to the operating 45 relays 201, 200, and 202 of the call indicator mechanism (Fig. 2). When relay 108 attracts its armature, the battery supply 50 through the winding of relay 113 is disconnected from conductors 100 and 101. Relays 113 and 112 in the trunk circuit are also deenergized at this time. In response 55 to the energization of relay 108, an energizing circuit is prepared in the sender for the impulse sequence switch. This sequence switch which serves to transmit code impulses to the distant office for setting the relay call indicator leaves position 1 and 60 advances in a continuous movement into posi-

tion 17. The code impulses are sent to the indicator mechanism over a full metallic circuit comprising both sides of the trunk line in series. These impulses may be of either positive or negative polarity dependent upon 70 which pole of the battery is connected to a given side of the line. They may be also weak or strong dependent upon whether a high or low resistance is included in the circuit. Relay 201 is polarized in such a manner as to respond only to an impulse created by a flow of current from the positive pole of the battery over conductor 137, and returning to ground by way of conductor 136. The relay 200 is polarized in such a manner 75 as to respond only to an impulse created by a flow of current in the opposite direction. Relay 202 responds to strong impulses of both positive and negative polarity but being marginal does not operate on weak pulses. 80

The operation of the impulse sequence switch in the sender in transmitting code impulses to the distant office for setting the relay call indicator is explained in detail in the patent to A. E. Lundell supra and accordingly a detailed description of this operation has been deemed unnecessary and is omitted for purposes of simplification. When the necessary code of impulses has 90 been sent to the call indicator mechanism in accordance with the assumed line designation 4432 for operating the proper thousands, hundreds, tens, and units shutter magnets, relays 327, 329, 334, 335 and 337 of the selecting relays of Fig. 3 will have been operated in a manner fully described in the patent hereinabove mentioned. 95

Relay 327 was energized in a circuit from ground at the left outer armature and contact of relay 219, left front contact and armature of operated relay 218, conductor 243, armature and contact of relay 202, outer right hand armature and back contact of relay 204, inner right hand armature and back contact of relay 209, conductor 225, left hand winding of relay 327 to battery and ground. Relay 329 is energized in a circuit from grounded conductor 243, armature and contact of relay 201, left hand armature and front contact of relay 205, outer right hand armature and contact of relay 210, outer right hand armature and front contact of relay 212, outer right hand armature and back contact of relay 214, conductor 230 left hand winding of relay 329 to battery and ground. 105 Relay 334 becomes energized in a circuit from grounded conductor 243, armature and contact of relay 201, left hand armature and back contact of relay 205, left hand armature 110 and front contact of relay 210, left hand armature and front contact of relay 212, outer left hand armature and back contact of relay 214, conductor 231, left hand winding of relay 334 to battery and ground. Relay 335 becomes energized in a circuit from 115 120 125 130

- grounded conductor 243, armature and contact of relay 202, outer right back contact of relay 204, inner right front contacts of relays 209 and 211, inner right back contact of relay 213, conductor 232, left winding of relay 335 to battery. Relay 337 becomes energized in a circuit from grounded conductor 243, armature and contact of relay 202, outer right hand armature and back contact of relay 204, inner right hand armature and front contacts of relays 209, 211, 213 in series, conductor 233, left hand winding of relay 337 to battery and ground. The necessary code of impulses has thus been sent to the call indicator mechanism for selecting the proper thousands, hundreds, tens, and units shutter magnets to advise the operator aurally of the designation of the desired line which it will be recalled is 4432. Since relay 327 of the thousands group is energized, the No. 4 thousands shutter magnet 324 is energized in the following circuit. Battery through the right hand armature and upper contact of relay 217, conductor 240, inner right hand armature and back contact of relay 339, left hand armature and front contact of relay 327, inner left hand armature and back contact of relay 340, the winding of shutter magnet 324, front contact and outer right hand armature of relay 327, outer left hand armature and contact of relay 340, outer right hand armature and back contact of relay 341, conductor 247, lower contact and left hand armature of relay 217 to the grounded conductor 243. It will be observed that relay 217 is energized by means of a circuit closed at the inner left hand armature and contact of relay 214 at the beginning of registration of the tens digit. The circuit for the energization of the No. 4 hundreds shutter magnet 326 may be traced from battery through the right hand armature and lower contact of relay 217, conductor 241, inner right hand armature and back contact of relay 342, left hand armature and back contact of relay 343, outer right hand armature and back contact of relay 344, left hand armature and front contact of relay 329, winding of shutter magnet 326, front contact and outer right hand armature of relay 329, conductor 228, upper contact and left hand armature of relay 217 to the grounded conductor 243. The circuit for energizing the No. 3 tens shutter magnet, 336, may be traced from battery through the contact and outermost right hand armature of relay 216, conductor 242, inner right hand armature and back contact of relay 345, left hand armature and front contact of relay 335, inner left hand armature and front contact of relay 334, winding of shutter magnet 336, back contact and inner left hand armature of relay 345 to the grounded conductor 244. The circuit for the units shutter magnet 338 may be traced from battery at
- the outer right hand armature and contact of relay 215, conductor 239, inner right hand armature and back contact of relay 351, left hand armature and front contact of relay 337, inner left hand armature and back contact of relay 352, winding of shutter magnet 338, front contact and outer right hand armature of relay 337, outer left hand armature and contact of relay 352, back contact and outer right hand armature of relay 353, conductor 290, contact and inner right hand armature of relay 215 to grounded conductor 243.
- When the units relay 215 energizes following the completion of registration of the units digit and the selected shutter magnet 338 is operated a circuit is closed from battery at the outer right contact of relay 215 (Fig. 4), conductor 400, contact of slow relay 424, conductor 401 through the winding of magnet 402 to ground. Magnet 402 is energized in this circuit and draws up its armature 403, removing the armature roller 404 from the roller depression 405 and makes possible the rotation of drums 406, 421, 422 and 423. A circuit for starting up motor 407 is then closed by armature 408 and contact 409 upon the operation of pivoted armature 403, the insulated pin 413 of which closes this circuit. This circuit may be traced from battery 410, armature 408, contact 409, conductor 411 through the motor windings to ground. A circuit in parallel with motor 407 is also closed through the slow relay 424 which after an interval opens the circuit of magnet 402, but not before the motor 407 has driven the drum 406 forward so that roller 404 is removed from depression 405 and rests on the end of the drum, holding contacts 408 and 409 closed. The light from lamp 412 which may be constantly lighted passes through a pin hole in the screen 416 interposed between said lamp and the pivoted armature 414 of shutter magnet 324. Armature 414 pivots on pin 415 and normally prevents the passage of the rays of light beyond its own surface.
- What is claimed is:
1. In a telephone system, a calling subscriber's line, called subscribers' lines, an operator's position equipped with a telephone set, a trunk circuit incoming to said operator's position for extending a connection to a called line, a device associated with said operator's position for impressing audible signals upon said telephone set, means at said position for interconnecting said device and said trunk circuit, means for transmitting codes of impulses over said trunk under the control of said calling subscriber and means responsive to said impulses for actuating said device to cause an audible announcement of the number of a desired called subscriber's line.
  2. In a telephone system, a calling sub-

scriber's line, an operator's position, a trunk incoming to said position, an audible signaling device at said position comprising a plurality of selectable light valves to permit ⁵ citation of photo-electric cells through films with striations thereon, means controlled at said position for associating said device with said trunk and means operable over said trunk for selecting variable combinations of ¹⁰ said light valves.

3. In a telephone system, a calling subscriber's line, a called subscriber's line, an operator's position, a trunk circuit incoming to said position, an audible signaling device ¹⁵ at said position comprising a plurality of selectable light valves to permit the excitation of photo-electric cells through films with striations thereon, means controlled at said position for associating said device with said trunk, means for transmitting codes of ²⁰ impulses over said trunk and means responsive to said impulses for selecting variable combinations of said plurality of light valves.

4. In a telephone system, a calling line, a called line, an operator's position, a plurality of trunk circuits incoming to said position, an audible signaling device common to said trunk circuits comprising a plurality of ²⁵ selectable light valves at said operator's position and a translating device controlled thereby, means controlled at said position for associating said device with one of said trunks and means operated over said trunk ³⁰ under the control of said calling line for actuating said device.

5. In a telephone system, a calling line, a called line, an operator's position, a trunk circuit incoming to said position, an audible ⁴⁰ signaling device at said position comprising a plurality of light valves and a translating device controlled thereby, an assignment key individual to said trunk for associating said device with said trunk, means for transmitting ⁴⁵ codes of impulses over said trunk and means responsive to said impulses for selecting variable combinations of said light valves.

6. In a telephone system, a calling line, a called line, an operator's position, a trunk circuit incoming to said operator's position, a registering device, a plurality of series of light valves, a light source individual to each light valve, a plurality of speech films with ⁵⁵ striations thereon, a light sensitive means individual to each of said plurality of films, means for associating said registering device with said trunk, an announcing device responsive to said light sensitive means and means operable over said trunk for setting ⁶⁰ said registering device to select variable combinations of said light valves for excitation of said light sensitive means from light directed through particular striations of said films.

7. In a telephone system, a calling line, a called line, an operator's position, a trunk circuit incoming to said operator's position, means for transmitting codes of impulses over said trunks, a signaling device at said ⁷⁰ position comprising a plurality of series of light valves, a plurality of rotary drums having striations thereon, a light sensitive means individual to each of said drums, an announcing device responsive to said light ⁷⁵ sensitive means and a locking mechanism for said drums, means responsive to said impulses for selecting variable combinations of said light valves, and means responsive upon the complete reception of said impulses ⁸⁰ for releasing said locking mechanism in order to rotate said drums.

8. In a telephone system, a calling line, a called line, an operator's position, a trunk circuit incoming to said operator's position, ⁸⁵ means for transmitting codes of impulses over said trunks, a signaling device at said position comprising a plurality of series of light valves, a plurality of rotary drums having speech record striations thereon, ⁹⁰ light sensitive means individual to each of said drums arranged for excitation from light through said striations and an announcing device responsive to said light sensitive means, means for locking said drums in their normal position, a magnet for controlling said locking means, a driving means common to said drums, means responsive to said impulses for selecting variable combinations of said light valves, means responsive upon the complete reception of said impulses ⁹⁵ for energizing said magnet to open said locking means and operate said driving means.

9. In a telephone system, a calling line, a called line, an operator's position, a trunk circuit incoming to said position, means for sending variable codes of impulses over said trunk, a signaling device at said position comprising a plurality of series of light ¹⁰⁵ valves selectively responsive to said impulses, a light source individual to each light valve, a rotary drum individual to each series of light valves, a plurality of speech film striations individual to each rotary drum, each one of said plurality of striations being individual to one of a series of light valves, means responsive to the operation of any light valve for focusing said light source on the striations individual to said light valve, and means responsive to the illuminated film striations for making an audible translation of said impulses.

10. In a telephone system, an operator's position, a trunk circuit incoming to said operator's position, means for sending variable codes of impulses over said trunk, a signaling device at said position comprising a plurality of rotary drums, a plurality of series of light valves, a plurality of speech films ¹¹⁰ ¹¹⁵ ¹²⁰ ¹²⁵ ¹³⁰

- having striations thereon and a light sensitive means individual to each of said drums, means responsive to said impulses for selectively operating one in each series of light 5 valves, means responsive to the operation of any one of said light valves for illuminating its associated speech film striations, means responsive to said last-mentioned means for excitation of said light sensitive means, 10 means for translating said impulses into verbal signals and means for amplifying the output of said light sensitive means.
11. In a telephone system, an operator's position, a trunk circuit incoming to said 15 operator's position, means for sending variable codes of impulses over said trunk, a signaling device at said position, comprising a plurality of rotary drums, a series of light valves, a plurality of speech films having 20 striations thereon and a light sensitive means individual to each of said drums, means responsive to said impulses for selectively operating one in each series of light valves and means for successively exciting the light 25 sensitive means individual to each of said plurality of drums for translating said impulses into successive audible announcements.
12. In a telephone system, a calling subscriber's line, called subscribers' lines, an operator's position, a trunk circuit incoming 30
- to said operator's position, means for extending a connection to the operator's position over said trunk from said calling line, means for sending variable codes of impulses over 35 said trunk, a signaling device at said operator's position comprising a plurality of rotary drums, a plurality of series of light valves, a plurality of speech films having striations thereon and a light sensitive means 40 individual to each of said plurality of rotary drums, means controlled at said position for associating said signaling device with said trunk, means responsive to said impulses for selectively operating one of each of said plurality of series of light valves, means responsive to the operation of said light valves for illuminating the speech film striations associated therewith, means responsive to said last-mentioned means for exciting said light 45 sensitive means for the translation of said impulses into audible announcements, means for driving said rotary drums, means responsive upon the complete reception of said impulses for actuating said driving means 50 and means for amplifying the output of said light sensitive means.

In witness whereof, I hereunto subscribe my name this 25th day of January A. D., 1926.

DONALD MACKENZIE.
